UNITED STATES PATENT OFFICE.

HERMANN LÜCKE AND PHILIPP BRÜMMER, OF WORCESTER, MASS.

IMPROVEMENT IN TICKET-CLASPS.

Specification forming part of Letters Patent No. **155,247**, dated September 22, 1874; application filed August 10, 1874.

To all whom it may concern:

Be it known that we, HERMANN LÜCKE and PHILIPP BRÜMMER, of Worcester, in the county of Worcester and State of Massachusetts, have invented a new and useful Improvement in Ticket-Clasps, of which the following is a specification:

The invention relates to the construction of the device, whereby it is adapted for clamping or holding tickets, and various other articles, as hereinafter fully described.

In the accompanying drawing, Figure 1 is a front view, and Fig. 2 is a longitudinal section of Fig. 1, taken on the line *xx*.

Similar letters of reference indicate corresponding parts.

This holder is constructed from a single piece of metal, but the thread-cutter is made separate and attached by solder or other means to the main plate, from which the various parts of the holder are formed.

A is the main plate. B is the ticket-holder or clamp, formed by bending and doubling over an extension of the main plate A. C is the pin by means of which the entire article is attached to the coat or vest of the user. D is the hook, which secures the pin to the clothing. E is a spring, which curves over the clamp B, and latches in the hook F, which protrudes through the clamp in the opening G of the ticket-holder B. H is a point cut from the clamp, which extends through an orifice in the plate A, which punctures the ticket and prevents it from being withdrawn. I is a spring-hook, at the lower end of the

main plate, upon which baggage-checks and similar articles may be safely confined. J is the pencil-holder, it being a lateral extension of the plate A, bent in a circle to form an eye and hold the pencil by friction. K is the thread-cutter, formed of a piece of metal, L, separate from the plate A, but attached thereto by means of solder, or in any permanent manner, having a curved slot, m, therein. In the slot m is fixed a steel blade, N. O is an opening which terminates in a point.

The thread to be cut is forced down into the acute angle of the opening, and is severed by its contact with the edge of the blade N.

This entire article, with the exception of the thread-cutter, is formed or cut (by means of suitably-contrived dies) from a single piece of sheet metal.

The holder may be made without the cutter, but we prefer to combine them, as it makes the article more complete and desirable to the public.

Having thus described our invention, we claim as new and desire to secure by Letters Patent—

The slotted plates A and B, the latter having point H and curved locking-spring E, and the former the terminal hook I, and provided with catch F, said parts forming a clamp, as shown and described.

HERMANN LÜCKE.
PHILIPP BRÜMMER.
